UNITED STATES PATENT OFFICE.

EDWARD FREDERICK RORKE, OF CHICAGO, ILLINOIS.

LABELING-MACHINE.

940,731.

Specification of Letters Patent. Patented Nov. 23, 1909.

Application filed November 27, 1908. Serial No. 464,632.

To all whom it may concern:

Be it known that I, EDWARD FREDERICK RORKE, a citizen of the United States, and resident of the city of Chicago, in the county 5 of Cook and State of Illinois, have invented a certain new and useful Labeling-Machine, of which the following is a specification.

My invention relates to machines for affixing labels to bottles, etc., and its object is 10 to provide such a machine that will be economical in construction and simple and effective in operation. This object is attained by, and my invention is embodied in, the following described mechanism illustrated by the accompanying drawings, in 15 which—

Figure 1 is a side elevation of my labeling machine; Fig. 2 is a plan view thereof; Fig. 3 is a vertical section of the same, on line 20 3—3 of Fig. 2; Fig. 4 is a transverse vertical section of the "wiping" apparatus; Fig. 5 is a transverse vertical section of the paste container; Fig. 6 is a vertical transverse section of the label container; Fig. 7 25 is a plan view of the locking device by which the radial arms 4, 5 and 6, are prevented from rotating; and Fig. 8 is a longitudinal vertical section of the label container.

From a suitable base 1 rise the supports 30 2, carrying a spindle or stud 3 on which rotate the radial arms 4, 5 and 6. Each of these arms is similarly bifurcated, having the fingers 7 as shown. A vertical shaft 8 rotated by suitable means as by the motor 9 35 driving the bevel gears 10 and 11, carries the circular disk 12: co-axial with this shaft 8 is the shaft 13 carrying the radial arm 14 adapted to engage by its pin 15 in one of the recesses 16 of a circular disk 17 borne 40 by the radial arms 4, 5, and 6, and concentric with their axis of rotation. Each engagement of the arm 14 rotates the radial arms 4, 5, and 6 one third of their revolution. During the intervals between successive 45 engagements of the arm 14 the radial arms 4, 5, and 6 are locked from turning by the pin 18 on the radial arm 19 carried on the same hub with the arm 14. This pin 18 is adapted to engage and travel in the arc slots 20 of

50 the circular disk 21 on the same hub with the disk 17, and thus prevent during such engagement the radial arms 4, 5, and 6 from rotating. The shaft 13 is rotated by the shaft 8 through the gears 48, 49, and 50 in 55 the direction opposite to the rotation of the driving shaft 8.

Carried by the base 1 and disposed at an angular interval of 120 degrees apart, are the paste container 22, the label container 23, and the wiping apparatus 24. The paste 60 container is provided with, and its open bottom is closed by, engaging elastic rolls 25 as particularly shown in Fig. 5, between which rolls the paste flows down. This paste container is provided with squared 65 lugs 26 spring-pressed downward at 27 and adapted to travel in longitudinal slots (as shown) in the supporting parallel arms 28 of a bell crank lever fulcrumed at 29 on the base 1. The other arm 30 of this bell 70 crank lever is preferably provided with a friction roll 31 which is engaged by a cam 32 carried by the disk 12, which engagement carries the paste container inward against the pressure of a spring 33 and dis- 75 tributes the paste by the contact of the lowest roll 25, on the fingers 7 of the particular radial arm 4, 5, or 6 which is at the time directly opposite the paste container.

The label container 23 has a short vertical 80 sliding movement on the base 1. It may have several vertical partitions—three in the construction shown, two of which are filled with the labels 35 pressed by weights 36. The lower ends of the spaces formed by 85 these partitions are slightly contracted, as shown in Fig. 6, sufficiently to retain the labels therein from falling through. The label container is provided with a horizontal arm 37 having preferably a friction roll 38 90 which is engaged by a cam 39 carried by the disk 12, which engagement presses the label container downward against the pressure of a spring 34 until the lowest label is pressed on the fingers 7 (to which paste has been 95 previously applied as heretofore stated) of the particular radial arm 4, 5, or 6 which is at the time directly opposite and below the label container. The label container rising by the spring 34 when the cam 39 passes out 100 of its engagement, the lowest label adheres to the fingers 7 and is carried around to a position directly opposite and under the wiping apparatus, for the third operation of the machine.

105 The wiping apparatus 24 has on either side a leaf 40 pivoted thereto and spring-pressed downward at 41 as shown. Directly underneath the wiping apparatus, a suitable cradle 42 adapted to hold the bottle 43 to be 110 labeled, has a vertical reciprocal movement on the base 1. The cradle and bottle rest in

a position (as shown in Fig. 3) slightly below the fingers 7 of the radial arms, until by the rotation of the disk 12 the cam 44 engages the friction roll 45 of the lever 46 5 fulcrumed at 47, which engagement carries against the pressure of a spring 51, the cradle and bottle upward, the bottle passing between the fingers 7 of the radial arm 4, 5, or 6 which is directly opposite and above it at the time, to which fingers the label 10 has been previously applied as above explained. As the bottle rises between the fingers 7, the label is thus removed from them, and by the leaves 40 is pressed or 15 "wiped" on the bottle and the labeling operation is complete. The cam 44 passing out of its engagement, the cradle and bottle descend and the bottle may be removed and a new bottle placed in the cradle, before the 20 rotation of the radial arms is resumed.

It will be seen that the three operations of applying paste to the fingers 7, removing a label from the label container by the fingers to which paste has been applied, and affixing 25 a label to a bottle, are accomplished simultaneously and during each successive cessation of the rotation of the radial arms.

From the foregoing description, the operation of my labeling machine is manifest.

30 It is evident that my invention may be embodied in other and varying mechanisms without departing from its scope and spirit, and I do not propose to confine myself to the details of construction above shown and 35 described.

I claim:

1. In a labeling machine having a paste container, a label holder, a wiping apparatus adapted to affix a pasted label to the 40 work, all circularly disposed, and a movable cradle adapted to hold the work, the combination of a rotatable arm adapted to move into the operative positions of said container, holder and apparatus, a rotatable 45 disk, means intermediate the disk and the arm to rotate the arm, means for applying paste from the container to the arm, means intermediate the disk and the label holder for carrying a label in the holder into contact with the paste so applied, and means intermediate the disk and the cradle for moving the cradle to carry said label and the work into operative engagement with the 50 wiping apparatus.

55 2. In a labeling machine, the combination of a paste container, a label holder, a wiping apparatus adapted to affix a pasted label to the work, a rotatable arm, a movable cradle adapted to hold the work, means for applying paste to the arm from the container, a rotatable cam-bearing disk, means intermediate the disk and the label holder to move by the rotation of the disk a label held in the holder into contact with the paste applied to 60 the arm, and means intermediate the disk 65

and the cradle to move by the rotation of the disk the cradle with the work and label into operative engagement with the wiping apparatus.

3. In a labeling machine, the combination 70 of a rotatable arm and a paste container adapted to apply paste to that surface of the arm which lies in the plane of its rotation and having for such purpose a movement in the longitudinal direction of the arm. 75

4. In a labeling machine, the combination of three rotatable radial arms spaced at equal distances apart, a paste container having a movement toward and from the axis of the arms' rotation, a label holder, a wiping 80 apparatus adapted to affix a pasted label to the work, said container, holder, and apparatus being circularly arranged at equal angular intervals, a movable cradle adapted to hold the work, means for rotating the arms 85 and intermitting such rotation at the operative positions of the machine, means for moving the container to apply paste to the arms, means for carrying a label in the holder into contact with the paste so applied, and means for moving the cradle to carry said label and the work into operative 90 engagement with the wiping apparatus. 95

5. In a labeling machine, the combination of a movable paste-container, a movable label-holder, a wiping apparatus adapted to affix a pasted label to the work, said container, holder and apparatus being circularly disposed, a movable cradle adapted to hold the work, a rotatable arm having 100 two fingers, a rotatable cam-bearing disk, means intermediate the disk and the paste container adapted to move the same into operative engagement with the fingers, means intermediate the disk and the label-holder 105 adapted to move a label held therein into operative engagement with the pasted fingers, and means intermediate the disk and the cradle to move the same and the work and said label into operative engagement with 110 the wiping apparatus.

6. In a labeling machine having a movable paste container, a movable label holder, a wiping apparatus adapted to affix a pasted label to the work, all circularly disposed, 115 and a movable cradle adapted to hold the work, the combination of a rotatable arm adapted to move into the operative positions of said container, holder and apparatus, a rotatable disk, means intermediate the disk and the arm to rotate the arm, means intermediate the disk and the container to move the same to apply paste to the arm, means intermediate the disk and the holder to move the same to carry a label into contact with the paste so applied, and means intermediate the disk and the cradle for moving the cradle to carry said label and the work into operative engagement with the 120 wiping apparatus. 125

7. In a labeling machine, the combination of three rotatable radial arms spaced at equal distances apart, a paste container having a movement toward and from the axis 5 of the arms' rotation, a movable label holder, a wiping apparatus adapted to affix a pasted label to the work, said container, holder and apparatus being circularly arranged at equal angular distances apart, a movable cradle 10 adapted to hold the work, a rotatable disk, means intermediate the disk and the arms to rotate the arms and to intermit such rotation at the operative positions of the machine, means intermediate the disk and the container 15 to move the same to apply paste to the

arms, means intermediate the disk and the holder to move the same to carry a label into contact with the paste so applied, and means intermediate the disk and the cradle for moving the cradle to carry said label and 20 the work into operative engagement with the wiping apparatus.

In witness whereof, I have signed my name to this specification in the presence of two subscribing witnesses.

E. FREDERICK RORKE.
